(57) **CLAIM**

The ornamental design for a air conditioner for a boarding bridge, as shown and described.

DESCRIPTION

FIG. 1 is a front perspective view of an air conditioner for a boarding bridge, showing our new design;

FIG. 2 is a rear perspective view of the claimed design;

FIG. 3 is a front view of the claimed design of FIG. 1;

FIG. 4 is a rear view of the claimed design of FIG. 1;

FIG. 5 is a left-side view of the claimed design of FIG. 1;

FIG. 6 is a right-side view of the claimed design of FIG. 1;

FIG. 7 is a top view of the claimed design of FIG. 1;

FIG. 8 is a bottom view of the claimed design of FIG. 1;

FIG. 9 is an enlarged partial view of the claimed design of FIG. 1;

FIG. 10 is an enlarged partial view of the claimed design of FIG. 2; and,

FIG. 11 is an enlarged view of the claimed design of FIG. 4.

The broken lines illustrate the environmental structure and form no part of the claimed design.

1 Claim, 9 Drawing Sheets
